UNITED STATES PATENT OFFICE.

EMANUEL SMITH, OF MURRAY, IDAHO.

PULVERIZER.

1,323,417.

Specification of Letters Patent.

Patented Dec. 2, 1919.

Application filed November 21, 1918. Serial No. 263,519.

To all whom it may concern:

Be it known that I, EMANUEL SMITH, a citizen of the United States, residing at Murray, in the county of Shoshone and 5 State of Idaho, have invented certain new and useful Improvements in Pulverizers, of which the following is a specification.

This invention relates to mills, and more especially to ore grinders and crushers; and 10 the object of the same is to provide a pulverizer which will prevent sliming but which may be used wet or dry.

The general idea of the invention is the reciprocation of a heavy member over a flat 15 base mechanically, provided with means for raising one end of this member slightly off the base at one limit of its stroke so as to admit a little more of the material being ground or pulverized; and the details of the 20 invention consists in the means for carrying out this broad idea, one successful method of doing so being set forth in the following specification and shown in the drawings, wherein:

25 Figure 1 is a plan view and

Fig. 2 a side elevation of this machine complete,

Fig. 3 is an enlarged cross section on the line 3—3 of Fig. 2,

30 Fig. 4 a still further enlarged sectional detail on the line 4—4 of Fig. 3, and

Fig. 5 a sectional detail on line 5—5 of Fig. 1.

In the drawings the numeral 1 designates 35 a base which may and preferably does include a removable wear face 2, and 3—3 are tracks of L-shaped cross section secured by bolts 4 upon the edges of the face 2 and upstanding therefrom. Between these tracks 40 reciprocates what I will call broadly the rubber 5, motion being imparted to it by a crank or eccentric 6 on a power shaft 7, through a pitman rod 8 or by any other suitable means, although this will answer. 45 The power shaft should carry a heavy fly wheel 9, and rotary motion may be imparted to this shaft by means not necessary to illustrate herein.

The rubber 5 has longitudinal upstanding ribs or flanges 10 along its sides, and 50 preferably two others near its center as indicated at 11, and near both the front and rear ends, all of these elements having upright slots 12 in which are movably mounted 55 blocks 13 best seen in Fig. 3. Each pair of

blocks has journals for a short shaft 14 carrying a roller 15 at its outer end which may travel on the track 3 and sustain more or less of the weight of the rubber, according as the blocks are adjusted in their slots. 60 On the tracks are disposed two wedges 16, each having an inclined face 17 as seen in Fig. 2 and over which the forward roller travels as the rubber is drawn toward the main shaft 7, and each wedge has a flange 65 18 depending alongside one of the tracks and provided with a slot 19. Through the latter passes a bolt 20 and by means of which the wedge may be adjusted forward or backward, thereby permitting the roller 70 to strike it earlier or later as desired. Besides this adjustment, the vertical adjustment of the shaft 14, and therefore of the position of the roller 15, will cause the latter to strike the face 17 earlier or later, and 75 therefore great nicety in such action may be had by means of the two adjustments.

Any suitable means may be employed for guiding the pair of blocks 13 in the slots 12 and for adjusting them vertically therein, 80 but as shown I prefer to provide each block in its lower end with a socket slidably mounted over a pin 22 which rises from the lower end of the slot 12. Also a screw 23 is passed down through the top of the flange 85 10 into the upper end of the block, where it is held by a pin 24 and after this screw is adjusted by turning its head 25, it is held in adjusted position by a lock nut 26 or by other suitable means. Thus the pin 24 90 which engages a groove 27 around the end of the screw, serves as means for swiveling the screw in the block, and the screw 23 at the upper end and pin and socket at the lower end of the block serve as means for guiding 95 and retaining it within its slot 12.

While this pulverizer may be used with success in the grinding of ores, I do not wish to be limited in that respect, nor in the details and proportions and materials of parts, 100 as various changes therein can be made without departing from the spirit of the invention. I do consider it advisable, however, to employ a fly wheel on the driving shaft which reciprocates the rubber, so that 105 obstructions to its reciprocations in the way of extra hard lumps of ore encountered may be overcome by the inertia of the fly wheel without throwing an undue load on the driving mechanism and without retarding or 110

stopping the reciprocatory motion of the rubber.

What is claimed is:—

1. In a pulverizer, the combination with a base having tracks along its side edges, a rubber movable bodily on the base between said tracks, and means for reciprocating said rubber; of rollers carried by the rubber above said tracks, wedges carried by the tracks and having inclined faces in the path of the rollers, and means for adjusting the position of the wedges on the tracks, for the purpose set forth.
2. In a pulverizer, the combination with a base having tracks along its side edges, a rubber movably mounted on the base between said tracks, and means for reciprocating said rubber; of shafts adjustably mounted on the rubber, each having a roller standing above one of said tracks, and wedges adjustably mounted on the tracks with the wedge faces in the path of said rollers.
3. In a pulverizer, the combination with a base having tracks along its side edges, a rubber movably mounted on the base between said tracks, and means for reciprocating said rubber; of shafts having rollers

standing above said tracks, means for mounting said shafts for vertical adjustment in the rubber, wedges disposed along side said tracks and having inclined faces overlying the tracks in the path of said rollers, and means for permitting the longitudinal adjustment of said wedges.

4. The combination with a base, a rubber movable thereon and having an upstanding flange with an upright slot therein, a shaft passing through said slot, rollers on both ends of the shaft, and wedges carried by the base and engaged by the roller when the rubber is reciprocated; of a block for the shaft mounted in said slot and having sockets in its upper and lower ends, a pin in the lower end of said slot engaging the lower socket, a screw through the upper end of the slot, and a swivel connection between the lower end of the screw and the upper socket in the block.

In testimony whereof I affix my signature in presence of two witnesses.

EMANUEL SMITH.
